CLAIM

The ornamental design for a interface for a floppy disc drive, as shown and described.

DESCRIPTION

FIG. 1 is a top, front right side perspective view of an interface for a floppy disc according to the present design;

FIG. 2 is a front elevational view thereof;

FIG. 3 is a top plan view thereof;

FIG. 4 is a right side elevational view thereof;

FIG. 5 is a left side elevational view thereof;

FIG. 6 is a rear elevational view thereof; and,

FIG. 7 is a bottom plan view thereof.

Fig. 1
